PASTE BRUSH HOLDER

Thomas J. Clark, Sr., Fort Worth, Tex.

Application March 2, 1953, Serial No. 23,852

Term of patent 3½ years

(Cl. D9—2)

To all whom it may concern:

Be it known that I, Thomas J. Clark, Sr., a citizen of the United States of America, residing at Fort Worth, in the county of Tarrant and State of Texas, have invented a new, original, and ornamental Design for a Paste Brush Holder, of which the following is a specification, reference being had to the accompanying drawing, forming part thereof.

The dotted line showing of a pail is for illustrative purposes only.

I claim:

The ornamental design for a paste brush holder, substantially as shown and described.
